UNITED STATES PATENT OFFICE.

MILLER REESE HUTCHISON, OF BRONXVILLE, NEW YORK.

SIGNALING-HORN, &c.

1,043,703.

Specification of Letters Patent.

Patented Nov. 5, 1912.

Application filed December 13, 1905. Serial No. 291,518.

To all whom it may concern:

Be it known that I, MILLER REESE HUTCHISON, a citizen of the United States, and a resident of Bronxville, in the county of Westchester and State of New York, have invented certain new and useful Improvements Relating to Signaling-Horns, &c., of which the following is a specification.

The invention herein set forth relates to 10 and concerns alarm or signaling horns, particularly those intended for use on automobiles and has for its object the production of a unitary device comprising a single mouth piece projector or horn, in combination with 15 two independently operated exciting means therefor, one constructed and arranged to excite signal vibrations of great amplitude and strength and the other to excite signal vibrations of characteristically less ampli- 20 tude and less strength. The vibrating means employed may be of the general character disclosed in my prior application Ser. No. 278,562 and my Patent, 956,898.

By this invention it is possible for the operator to have the most efficient long distance signal for use in the country, when proceeding at high speeds, and the softer signals in town, or when proceeding at low speeds. At the same time, the arrangement 25 may be such that the louder signal, will be instantly available, even in town, for use, should any great emergency arise to justify its employment. Two of the practical ways 30 of accomplishing this will be more fully understood by detail description in connection 35 with the accompanying drawings in which—

Figure 1 shows a two strength horn in side elevation. Fig. 2 shows a racing model two strength horn with single controlling 40 means and circuits. Fig. 3 is a vertical section of an efficient loud sounding vibrator together with means for changing to the softer note.

By reference to Figs. 1 and 2 it will be 45 seen that the horn or projector or mouth piece may be a long straight horn as indicated in Fig. 2, or it may be of the more conventional shape of curved horn indicated at 1^a, Fig. 1. In either case the horn has 50 associated with it in operative relation the two vibrators 4, 5, which, as explained above, are of characteristically different sound producing intensities, one of them, as 4, being adapted to produce the very loud 55 signal desired for use when proceeding at high speed or in cases of emergency and the

other, as 5, being adapted to produce the characteristically low intensity signals desirable for use where the louder signal is unnecessary and would be undesirable. The 60 vibrators 4 and 5 may be of any desired type but are preferably of the type wherein the vibrator is a diaphragm actuated by suitable means, as, for instance, by an electromagnet energized by intermittent currents 65 after the manner indicated in my said prior application Serial No. 278,562, filed September 15, 1905, wherein the interrupter is located within the magnet and diaphragm case or it may be of the type shown in my application Serial No. 280,910, filed October 2, 1905, now Patent 956,898, the latter being selected for illustration in Fig. 3 hereof. It 70 will be understood that the details of construction by these excitors for the horn are 75 not claimed here nor are they essential to practise of my present invention.

The circuits may be such as shown in Fig. 2 wherein the controller 6 comprises three spring members 7, 8, and 9, one of them, 8, 80 being connected with a battery and the other two with parallel conductors 11 and 12 extending to the loud and soft sounders 4 and 5, respectively. The circuit is completed by common lead to the battery 10. In operation, 8 may be forced into contact with either 85 7 or 9, at will, thereby closing circuit either through the loud or soft sounder as may be desired. Obviously 9 may be forced into contact with 8 and by further movement 8 90 forced into contact with 7, thereby closing both circuits in parallel and sounding both horns. Separate batteries may be similarly controlled from one switching device.

In Fig. 3 I have indicated for purposes of 95 illustration various ways in which the resonance of the air column of the horn may be damped or impaired or the amplitude of the vibration of the diaphragm decreased. This may be accomplished by seriously disturbing any of those adjustments which I have described in my prior application and prior patent above referred to as desirable to produce the loudest notes in the horn. For instance, the resonator diaphragm 24^a 100 may be moved out of position of resonance or the core of the electro-magnet may be moved out of effective range of the diaphragm by screwing rearwardly the bridge 34^a supporting the same. A screw 76 provided with a thin yielding or elastic damping member 77 forming an elastic cushion- 105 110

ing device may be screwed against the dia-
phragm with any desired degree of pressure
to impair the effectiveness thereof. The
horn 1 may be provided with a slot 80 adapt-
ed to register with a slot 81 in the case. It
5 may be held in any desired position by set
screw 82. For loud signals the horn 1 will
be turned so that the slot 80 is out of register
with the slot 81 and for softer signals it will
be turned so that said slots are in register.
10 Any other means of impairing resonance of
the air column may be employed.

It will be obvious to those skilled in the
art that the circuits of the vibrators 4, 5 in
15 Fig. 1 may be the same as those shown in
Fig. 2 or they may be independent circuits
carrying currents of different strengths, the
desired strength being determined either by
the power of the battery or by the amount
20 of resistance inserted in one or both circuits.

I claim—

1. An alarm horn or pipe in combination
with two exciting vibrators therefor, of
characteristically different intensities and
25 both in operative relation to the air column
of said horn.
2. An alarm horn and a plurality of elec-
tro-magnetic vibrators therefor, of char-
acteristically different intensities and both in
30 operative relation to the same air column of
said horn.
3. An alarm horn and two separate elec-
tro-magnetically operated diaphragms of
characteristically different intensities of vi-
35 bration and both in operative relation to the
air column of said horn.

4. An alarm or signal device comprising
a horn, in combination with a vibrator and
actuating means in operative relation to said
horn, constructed and arranged to excite sig-
40 nal vibrations of great amplitude and
strength in said horn, and another vibrator
and actuating means also in operative rela-
tion to said horn, operating independently
45 of said first mentioned vibrator, and con-
structed and arranged to excite therein sig-
nal vibrations of characteristically less am-
plitude and less strength, for the purpose de-
scribed.

5. An alarm or signaling device including
a horn in combination with a vibrator com-
prising a diaphragm arranged in operative
sound-producing relation to the air volume
50 of said horn, actuating means in operative
relation to said diaphragm and constructed
and arranged to cause signal vibrations of
great amplitude and strength in said horn,
and another vibrator and actuating means
55 also in operative relation to said horn and
operating independently of said first-men-
tioned vibrator and constructed and ar-
ranged to cause therein signal vibrations of
characteristically less amplitude and less
strength for the purpose described.

Signed at New York city, in the county of
60 New York and State of New York this
eleventh day of December, A. D. 1905.

MILLER REESE HUTCHISON.
